UNITED STATES PATENT OFFICE

SOLOMON WISE, OF CINCINNATI, OHIO

LOCK

Application filed June 17, 1927. Serial No. 199,600.

My invention relates to locks which employ a series of concentric tubes as tumblers, said tubes being pressed by springs into a normal break joint relation that prevents operation 5 of the lock, and a key being provided which will bring the tubes to a break joint relation.

It is the object of my present invention to so arrange such a lock as to permit of operation of a latching element by means of a 10 rotary key. As incidental objects are the provision of an economical structure formed of pressed steel or brass parts which can be readily assembled, and are to a large degree resistant to tampering.

15 I have illustrated but one embodiment of my invention, but it will be understood that there are numerous ways in which the principles illustrated in my drawings, and in detail described, can be applied in the construction 20 of locks. In theory the principle of construction is to employ an outer shell and inner shell in which is contained a revolving element that carries a suitable projection that will operate the lock. Within this revolving 25 element is an eccentric member containing one of the sets of tubular plungers. This member is held against rotation however by the shell structure of the device so that it will only slide. The shell structure also acts as 30 a stop for the rotation of the revolving element.

In another chamber in the revolving element is a set of plungers or tumblers, co-operating with the eccentrically arranged set at 35 the two ends of movement of the lock, but off center with the eccentrically arranged set at other times.

The key is applied to the second set of tumblers bringing out of break joint relation 40 with the eccentric set, and the fit of the key into the revolving element, results in the imparting of revolution thereto.

As a result the key is universal to the extent that it can be made symmetrical and be 45 inserted with either side up, when locking or unlocking whatever latch element is being employed.

It is a mere shift of parts to have both 50 tumbler arrangements eccentric, to the lock

casing, and to use a key which is not symmetrical.

Also the revolving member can be made differently, and the mode of operation essentially as just above described, maintained. 55

I accomplish my invention by that certain construction and arrangement of parts to be hereinafter more specifically pointed out and claimed.

In the drawings:

Fig. 1 is a central longitudinal section taken through the illustrated form of my lock showing it in locked position.

Fig. 2 is a like view showing the lock in the process of being revolved.

Fig. 3 is an inner end elevation of the lock in the position shown in Fig. 1.

Fig. 4 is a like view to Fig. 3 showing the lock in the condition illustrated in Fig. 2.

Fig. 5 is an end elevation of the outer face 70 of the lock.

Fig. 5^a is a view of a key.

The lock as illustrated is formed with an outer shell 1, which has the key hole plate 2 therein, the key hole 5 being circular with 75 two branch slots extending therefrom. Within this outer shell, which is of pressed steel, is the inner bushing or plug 3. The shell 1 is closed at the inner face as at 4, and the inner member 3 is closed, acts as a sleeve for 80 the revoluble member. This plug 3 with the parts contained therein, is properly located within the shell, and the edge 6 of the shell is spun over the key hole plate, the fit and turning in of the edge over the key hole 85 plate serving to hold the inner shell rigidly in place.

Within the shell and bushing or plug is the revolving member 7, which has an eccentric bore 8, and a concentric bore 9. A key hole 90 guard plate as at 10, may be set inside of the dished key hole plate.

The face 4 of the shell is formed with a semi-circular slot 11, through which projects a pin 12 that is on the revolving member. 95 The slot thus defines the limit of movement of the revolving member, and the pin is used to operate whatever latch is desired.

The face 4 of the shell also has a slot 13 therein, which acts to guide and maintain the 100

position of the eccentric tumbler member. This member is formed with an oval outer shape as indicated at 14, within which is a circular hole 15. The tubular tumblers 15^a to the number desired, are arranged concentrically within the hole, with springs 16 behind them to urge them outwardly from the hole. The body 14 has a rib 17 thereon which lies within the slot 13 in the shell.

10 The member 14 lies within the bore 8 which is of a size to fit its lengthwise dimension and the tubular tumblers when normally in position will project into the circular central bore 9 of the revolving member 7, (Fig. 1), from 15 the member 14.

15 Also located within the bore 9, which projects to the outer face of the revolving member, are the matching set of tubular tumblers 18.

20 The bore 9 has two slots 19 in its outer portion which engages the sides of the key, indicated by dotted lines at 20 in Fig. 2.

25 As now described, the lock is operated as follows, beginning with the parts as shown in Figs. 1 and 3. The key is inserted through the key hole slot (Fig. 5), with which the slot in the key hole guard plate is aligned, and is pressed inwardly sufficiently to cause the tumblers 18, to press inwardly on the tumblers 15^a, until a line of cleavage is established and the break joint relation of the tumblers is overcome. The key will when inserted find its side edges within the grooves within the bore 9 of the revolving member, 35 and when the key has been pressed inwardly sufficiently to break the locked tumbler arrangement, it can then be revolved to turn the revolving member.

30 The act of imparting the thrusting movement will be to force all of the plungers in the eccentric member within the confines of said member, so that as the revolving member starts to move they will feed across the inner face of the bore 9, and the thrust pressure on the key need not be maintained because the tumblers will be out of line with the bore 9.

35 As the revolving member moves the eccentric member will stay in the same plane but will slide as to the ridge thereon, lengthwise of the slot in the inner shell. At the end of one fourth revolution of the key, the ridge will be as far down in the slot as it will go, as shown in Fig. 4, and it will then rise again, the point being that the eccentric casing, at 45 the end of the locking operation will be back in its exact starting position, i. e. the end of a half revolution of the key.

40 When the revolving member is moved in opening direction as far as it will go, the key may be removed, and the lock will stay open until an insertion of the key, and a reversal of the movement of opening. Upon the withdrawal of the key the tumblers will snap back 45 into break joint relation in both open and closed position.

Once the tumblers are in break joint relation the structure will not operate, since the attempt to revolve the active member, would be to move the eccentric member in an eccentric path which it cannot take because the tumblers 15^a lying within the bore 9 will hold the eccentric member on the true center of the revolving or active member. The forcing of the lock is thus prevented by solid metal entirely across the structure and the shell prevents the whole inner structure from turning because of the ridge 14 and slot 13.

Having thus described my invention what I claim as new and desire to secure by Letters Patent is:

1. In a lock, the combination of a casing, a member revolvable within the casing, and having a projection extending therefrom to operate a suitable structure to be locked, a tumbler container held against rotary movement within the casing, a movable tumbler container portion within the revolvable member but held against revolution therewith, and concentric tubular tumblers in said container and container portion, spring pressed to maintain a normal break joint relation, whereby means, as a key, may be caused to revolve said member and to act upon one set of tumblers so as to eliminate the break joint relation of the sets.

2. In a lock the combination of a casing, a member revolvable within the casing and having a projection to operate a suitable structure to be locked, a tumbler container within said revolvable member held against rotary movement within the casing, and having a bore for tumblers said container being movable to bring said bore eccentric to the revolvable member, a tumbler container portion within and concentric to the revolvable members, matching tubular concentric tumblers in said bore and container portion, same being spring pressed to normal break joint relation when the bore is in line with the container portion, whereby means as a key may be caused to revolve the revolvable member, and to act upon the tumblers to dis-establish the break joint relation thereof.

3. In a lock the combination of a casing, a movable member revolvable within the casing, means retained movably but in non-revolvable position within the casing and adapted to retain said revolvable member against turning, and means revolvable with the said member, tubular co-axial tumblers forming part of said two means, whereby means as a key can be used for bringing said tumblers to a position where said non-revolvable means does not interfere with the movement of the revolvable member, and an element operated by one of the movable parts above referred to, for actuating a desired mechanism.

4. In a lock, a pair of tubular concentric tumbler holders, tumblers in said holders, arranged when the lock is in locked position to
